(Continued)

Primary Examiner — Rhea Shields(74) *Attorney, Agent, or Firm* — Gearhart Law LLC;
 David Postolski, Esq.(57) **CLAIM**

We claim the ornamental design for a nasal filter, as shown and described.

DESCRIPTION

FIG. 1 is a perspective view of a nasal filter.
 FIG. 2 is a front elevational view of FIG. 1.
 FIG. 3 is a side elevational view of FIG. 1.
 FIG. 4 is a top elevational view of FIG. 1.
 FIG. 5 is a bottom elevational view of FIG. 1.
 FIG. 6 is an exploded view of FIG. 1; and,
 FIG. 7 is a cross-sectional view taken along line 7-7 of FIG. 2.
